UNITED STATES PATENT OFFICE

145,117

DESIGN FOR A THEATER SIGN

Richard L. Byrd, Dallas, Tex.

Application June 15, 1945, Serial No. 120,131

Term of patent 14 years

(Cl. D1—12)

To all whom it may concern:

Be it known that I, Richard L. Byrd, a citizen of the United States, residing at Dallas, in the county of Dallas and State of Texas, have invented a new, original, and ornamental Design for a Theater Sign, of which the following is a specification, reference being had to the accompanying drawing, forming a part thereof.

The characteristic features of my design reside in the portions shown in full lines.

I claim:

The ornamental design for a theater sign, as shown and described.
